BATH FIXTURE LUG

Filed July 1, 1929

UNITED STATES PATENT OFFICE

WILLIAM J. WOOLLEY, OF CHICAGO, ILLINOIS

BATH-FIXTURE LUG

Application filed July 1, 1929. Serial No. 375,187.

This invention relates in general to improvements in bath fixture equipment, and has more particular reference to a combined flow and waste valve operating fixture which is adapted to support and to locate a drain or waste valve operating device in its co-operative relation with a drain valve.

A principal object of this invention is to provide a simple bath fixture in which the drain or waste valve operating device is adjustably positionable in operative relation with a drain valve.

An important object of the invention is to provide a flow valve operating fixture with a lug for mounting a drain valve operating mechanism in a predetermined position.

Another important object of the invention is the provision of an improved waste operating device for bath tubs.

Another object of the invention is to provide a simple means for attaching a drain valve operating device to a bath fixture and for securing it thereto so that the drain or waste valve operating device will be in operable position with respect to the waste valve.

A further object of the invention is to provide a combined flow and waste valve operating fixture for bath fixture equipment with a lug on a fitting for supporting the fittings of the waste valve operating device back of a wall of a bathroom, the lug being a substitute for an extra plate.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a portion of a bath fixture equipment embodying the principles of the invention;

Fig. 2 is an enlarged view, partly in section, of a portion of the bath fixture equipment shown in Fig. 1;

Fig. 3 is a section taken substantially on the line 3-3 of Fig. 2;

Fig. 4 is a section taken substantially on the line 4-4 of Fig. 3, and

Fig. 5 is a similar view to that of Fig. 4

showing the drain or waste valve operating device in the position for closing the drain valve.

For the purpose of illustrating the invention, the drawings show a portion of a bath fixture equipment adapted for use in connection with a bathtub and an overhead shower (not shown) and having flow or supply pipe fittings 5 which are usually concealed in a wall of the bathroom and which communicate through suitable valves 21 with a combined T and L-pipe 7 for supplying water to a usual bathtub (not shown) through a common pipe fitting 5' shown depending from a T-arm of the pipe 7. The pipe fittings 5 also communicate through the valves 21 with up-standing pipes 22 which may communicate through suitable valves and pipe fittings (not shown) with another bath outlet for supplying water to a usual shower head (not shown) which may extend out from a wall of the bathroom above the bathtub. The valves 21 are controlled by suitable handles 14 on the outer ends of valve stems 23 which, it will be understood, extend outwardly from the valves through a wall of the bathroom and through suitable escutcheon rings 24 to provide means for controlling the flow of water to the bathtub (not shown).

A lug or arm 6, substantially rectangular in transverse section, is cast integrally with the combined T and L-pipe 7 and extends therefrom horizontally and inwardly to a point substantially midway between the handles 14, as shown in Fig. 1, for the purpose of supporting and locating a drain or waste valve operating device, generally designated by the reference character 8, in co-operative relation with a drain or waste valve, schematically shown at 25. To this end, a horizontal aperture 6' is provided in the lug 6 near its free end to receive a loose-fitting sleeve bearing 10 which is secured in the aperture 6' by a set screw 11, as shown in Figs. 2 and 3.

A waste valve operating shaft 12 is journaled in the bearing sleeve 10 and extends outwardly therefrom, through a wall of the bathroom and an escutcheon ring 26, to a suitable handle 13 mounted on the outer end

of the shaft 12, as shown in Fig. 1. The handle 13 provides a means for rotating the shaft 12 in the sleeve 10 whereby to actuate the waste valve operating device 8. The shaft 12 extends inwardly beyond the inner end 5 of the bearing sleeve 10 and has its inner end knurled, as at 12', to receive a thrust disk 15 eccentrically mounted on the knurled portion 12' of the shaft 12 adjacent the inner end of the sleeve 10, the disk 15 thus being 10 adapted to rotate with the shaft.

A head 19 is cast to provide a substantially rectangular cam yoke 27 at its upper end and an outwardly extending, horizontal arm 28 at its lower end. The yoke 27 is arranged between the eccentrically mounted disk 15 and a flange 16' of an outer disk 16 mounted on the knurled end 12' of the shaft 12 adjacent the disk 15. The disk 16 is mounted to rotate 20 with the shaft 12 and is held thereon by a screw 17 which passes through the end of a hub portion 29 and threads into the end of the shaft 12 as shown in Fig. 3. It will be understood that the waste valve 25 is suitably 25 attached to a valve operating stem 9, which is externally threaded at its upper end 31 to engage in one of a plurality of internally threaded apertures 32, which are provided in the horizontal arm 28 of the head 19. The stem 9 is adjustably locked in the aperture 32 by means of a lock nut 33, as shown in Figs. 3 and 4.

The hub portion 29 of the disk 16 extends outwardly from the flange 16' eccentrically 35 of the flange and provides a seat for the upper side of the yoke 27 between the disk 15 and the flange 16' when the waste valve 25 is closed, as shown in Fig. 5. An inwardly extending cam lug 18 is cast on the inner face of 40 the disk 16 in spaced relation with the hub portion 29 to provide the maximum cam throw of the yoke 27 and is adapted to raise the cam lever from the closed position to the open position when the shaft 12 is rotated by 45 the handle 13 as shown in Figs. 3 and 4. The cam lug 18 is substantially rectangular in section, extending cord-like, nearly across a portion of the disk 16 near its periphery. The ends of the lug 18 are substantially semi-circular to co-operate with the arcuate corners 50 of the cam yoke 27 in raising or lowering the lever 19 to operate the waste valve 25.

The apertures 32 in the arm 28 of the cam lever 19 provide alternate positions for the 55 valve operating stem 9 and provide adjustments assuring a mounting for the stem 9 which is in operative relation with the waste valve 25. It will be understood that the lug or arm 6 is cast on the pipe fitting 7 in such 60 a way that the waste valve operating device 8 is automatically located in the proper vertical registration with the waste valve of the tube. Thus, the necessity of providing the heretofore usual separate mounting plate for 65 the drain valve operating device will be ob-

viated and there will be no such separate plate secured in the wall of the bathroom, thereby eliminating the extra work, expense and trouble in mounting the plate so that the drain or waste valve operating device and the 70 drain valve would be in correct operative relation with each other.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A bath fixture, comprising a flow valve operating device having an arm formed integrally therewith, and a waste valve operating device adapted to be supported by said arm.

2. A bath fixture, comprising a flow valve operating device having an arm formed integrally therewith, and a waste valve operating device adapted to be supported by said arm, said arm being formed to locate said waste valve operating device in operative relation with the waste valve.

3. A bath fixture arrangeable in the wall of a bathroom, comprising a flow valve operating device having an arm projecting therefrom, a shaft rotatably mounted in an end of said arm, a cam lever supported at an end of said shaft, and a waste valve operating stem adjustably supported by said cam lever.

4. A bath fixture arrangeable in the wall of a bathroom, comprising a flow valve operating device having an arm projecting therefrom, a shaft rotatably mounted in an end of said arm, a cam lever supported at an end of said shaft, and a waste valve operating stem adjustably supported by said cam lever, said lever being formed to provide a plurality of 110 positions to adjustably support and to locate said stem in operative relation with the waste valve.

5. A bath fixture arrangeable in a wall of a bathroom, comprising a pipe fitting having an arm formed integrally therewith, a shaft rotatably mounted in an end of said arm, a disk eccentrically mounted near an end of said shaft and adapted to rotate therewith, a cam mounted on an end of said shaft and adapted to rotate therewith, said cam having a hub portion and a cam lug adjacent said disk, and a cam yoke having a valve operating arm at one end, said yoke being positioned between said disk and said cam and engageable by said hub portion and said cam lug to provide valve operating movement for said operating arm.

6. A bath fixture arrangeable in a wall of a bathroom, comprising a pipe fitting having

ing an arm formed integrally therewith, a shaft rotatably mounted in an end of said arm, a disk eccentrically mounted near an end of said shaft and adapted to rotate therewith, a cam mounted on an end of said shaft and adapted to rotate therewith, said cam having a hub portion and a cam lug adjacent said disk, an adjustable valve operating stem, and a cam yoke having a valve 10 operating arm at one end, said yoke being engageable by said hub portion and said cam lug between said disk and said cam, and said arm having a plurality of apertures for adjustably locating said stem in operative 15 relation with the valve.

7. A bath fixture arrangeable in a wall of a bathroom, comprising a rotatable shaft, a disk eccentrically mounted near an end of said shaft and adapted to rotate therewith, 20 a cam mounted on an end of said shaft and adapted to rotate therewith, said cam having a hub portion and a cam lug adjacent said disk, and a cam yoke having a valve operating arm at one end, said yoke being 25 positioned between said disk and said cam and engageable by said hub portion and said cam lug to provide valve operating movement for said operating arm.

8. A bath fixture arrangeable in a wall of 30 a bathroom, comprising a rotatable shaft, a disk eccentrically mounted near an end of said shaft and adapted to rotate therewith, a cam mounted on an end of said shaft and adapted to rotate therewith, said cam 35 having a hub portion and a cam lug adjacent said disk, an adjustable valve operating stem, and a cam yoke having a valve operating arm at one end, said yoke being engageable by said hub portion and said cam lug between said disk and said cam, and 40 said arm having a plurality of apertures for adjustably locating said stem in operative relation with the valve.
